UNITED STATES PATENT OFFICE.

CHARLES C. WEST, OF MANITOWOC, WISCONSIN, ASSIGNOR TO MANITOWOC SHIP
BUILDING & DRY DOCK COMPANY, OF MANITOWOC, WISCONSIN, A CORPORA-
TION OF WISCONSIN.

SAND-BARGE.

1,127,137.

Specification of Letters Patent.

Patented Feb. 2, 1915.

Application filed October 9, 1912. Serial No. 724,752.

To all whom it may concern:

Be it known that I, CHARLES C. WEST, a citizen of the United States, and a resident of Manitowoc, in the county of Manitowoc and State of Wisconsin, have invented certain new and useful Improvements in Sand-Barges, of which the following is a specification, reference being made to the accompanying drawings.

10 My present invention relates generally to an improved method of unloading barges, or the like, engaged in the transportation and handling of sand and similar material, and more particularly to improved conveying and unloading apparatus in connection therewith.

20 One of the principal objects of my invention is the provision of novel means by which sand dumped into a hopper may be quickly unloaded in a practically dry condition. Another object of my invention is to provide improved means adapted to supply liquid to a hopper as a carrying medium to convey sand to a point of localization for unloading.

25 A further object is the provision of novel apparatus by means of which the carrying medium is quickly separated from the sand, the former being returned to the hopper for re-utilization, and the latter conditioned for economical handling and prompt unloading to a dock or elsewhere.

30 These and such other objects as may hereinafter appear or are incident to my invention I attain by means of a construction illustrated in preferred form in the accompanying drawings, wherein:—

35 Figure 1 is a longitudinal section of a barge employing my invention.

40 Figure 2 is a transverse section of Figure 1 on the line II—II.

45 Figure 3 is a sectional view showing my improved separator as applied to a barge.

50 Figure 4 is a slight modification of the separator illustrated in Figure 3.

55 Broadly stated, this invention comprises a novel apparatus adapted; first, to apply a carrying medium, as water, to sand in hoppers in such a manner that the sand near outlets therein will be sufficiently saturated to gravitate freely to a suitably situated conveyer; second, to provide coöperating means in this connection to effectually prevent clogging of such conveyer and also to maintain an even level of sand flow in the hopper;

third, to separate the water from the sand, leaving the sand in a comparatively dry state and so localized and situated that it can be quickly handled by ordinary unloading means and conveyed to a dock, or elsewhere; fourth, to return the water with little or no loss to the remaining sand in the hopper for further and continued use as a carrying medium.

60 In carrying out my invention as illustrated in the preferred manner, I provide a barge 5 having a hopper 6 whose sides 7 are inclined inwardly toward the central bottom portion 8. Positioned longitudinally beneath the hopper is a main conduit or conveyer 9 communicating with outlet openings 10 in the hopper through connecting pipes 11, which openings are conveniently arranged to tap the load at all necessary points.

65 The letter A indicates a pump connected to a supply pipe 12 which extends through the hull of the barge as at 5^a, said pump being further connected to a main water pipe 14 by means of a connection 15. The main 70 water pipe 14 extends longitudinally below and above the load to form a lower extension 16 and an upper extension 17 respectively, the lower extension 16 being positioned adjacent the main conveyer 9 and 75 connected thereto at intervals by means of the pipe connections 18 shown preferably slanting in a direction away from the pump A, and is further provided at points intermediate its length with branch pipes 19 80 which project into the hopper through the central portion and adjacent each of the outlet openings 10, the pipes being preferably controlled by valves 19^a. The upper extension 17 of the pipe 14 is suitably perforated 85 throughout its length for the application of a jet stream upon the level of the load in the hopper when desired.

90 The main conveyer 9 is also provided with a connection 9^a at one end communicating 100 with the pipe 14, the other end being connected to a suction pump B which carries a vertically extending pipe 20, the depending upper end of which projects into a separator or tank 21 preferably positioned above the 105 plane of the hopper or deck by means of supports 22, said tank having a contracted outlet opening 21^a and a controlling valve 25 situated at its lower extremity and adjacent to a belt conveyer 23.

Communicating with the upper portion of the tank is a return pipe 24 preferably having a bifurcated lower end as at 24^b in close proximity to the hopper, the other end of the pipe being within the tank and provided with an enlarged portion or receiving opening 24^a as shown in Figure 3, or as disclosed in a modified form in Figure 4.

The preferred arrangement of a plurality of conveyer, water, and branch pipes is clearly illustrated in Figure 2, though it is apparent that any similar embodiment such as a system of piping employing only one or more of each of these members, or any variation thereof, is deemed within the scope of this invention as pointed out in the appended claims.

Should a barge employing my invention be engaged in regular sand sucker service, the hoppers may be loaded by the unloading pump B through usual connections. Furthermore the loading can be accomplished by any suitable means and under no restrictions, as the material may be dumped in the hoppers or bins at any desired point without interference from parts, or interfering with exposed mechanism, which is a distinct advantage over other types.

The unloading operation is as follows: The hoppers being loaded, the pump A is started up forcing water from the supply pipe 12 through the connection 15 to the main water pipe 14 and into its extensions 16 and 17. The branch pipes 19 have their nozzles directing a jet toward the sand at the outlet openings 10, so that the sand becoming semi-liquid gravitates into the main conveyer 9 through the connections 11.

The perforated extension 17 located approximately above the load may be supported if desired by the ends of the hopper, or if the hopper is divided into two or more bins by partitions, other, or additional, means of support to this extension is afforded as shown in Figure 1 at 6^a. The water passing through the perforations permit an accumulation of water on top of the load tending to obtain movement of the sand to an even level in the hoppers.

The suction pump B being then put into operation, the resultant mixture flows from the hopper outlets through the pipe connections 11 to the conveyer and is drawn up through the pipe 20 into the tank 21 in which the mixture separates, the sand settling and passing through the contracted opening 21^a in a comparatively dry state and is carried away by a belt conveyer, or the like, to a dock or elsewhere. The water in the tank is returned for re-use by the overflow pipe 24, the bifurcated end of which is particularly adapted for use when the hopper is divided into bins as will be readily understood. In order to absolutely eliminate any tendency of the mixture to clog

the main conveyer 9, it is apparent that the suction developed therein will induce a continuous supply of liquid from the main water pipe 14 at 9^a and also from the extension 16 through the series of inclined pipes 18 to flush this passage. It is obvious that when the pump A has created a supply of liquid in the suction pipe or conveyer 9 and the sand at the outlets has become semi-fluid, a continuous head over the suction of the pump B is afforded. If desired the pump A may be stopped any time after the commencement of the flow of water into the hopper from the return pipe 24, as the operation has reached a stage where the water can be utilized over and over again, as the addition of the overflow keeps the sand sufficiently fluid for its removal by the suction pump B. This is one of the important features of my invention.

This method of separating the resultant mixture by means of my improved apparatus, and localizing the sand where it can be readily handled and quickly conveyed in a comparatively dry state to any required place of deposit, is a great advantage over existing unloading facilities. The methods commonly used necessitate unloading directly from the hoppers or bins by a flight of buckets involving constant change of position and shifting of mechanism; or in pumping directly from the bins, having the usual percentage of added water, it has been found difficult to maintain a constant head over the suction pump, and the mixture when unloaded on a dock still retains its fluidity and is consequently difficult to handle.

My improved means permits rapid unloading of the material and eliminates many disadvantages of other types of apparatus. The inclined sides of the hopper facilitate downward movement of the material toward the outlet openings. There are no involved parts to get out of order, and most of the piping and connections are out of the way and still are readily accessible. The entire apparatus is simple in construction and its operation is economical, rapid, and efficient.

It is not my intention to restrict myself to the exact embodiment as shown in the preferred construction, as it is obvious that certain structural variations may be made, without in any way departing from the spirit and scope of my invention as expressed in the appended claims.

Having thus described my invention and illustrated its use, what I claim as new and desire to secure by Letters Patent is the following:

1. A sand barge having a sand containing hopper formed with a discharge outlet in its base, a separating receptacle suitably supported in the barge above the plane of the hopper outlet and provided with an inlet

- opening and a discharge opening located below the inlet, a suction conduit connecting the hopper outlet and the inlet of the receptacle, transfer means positioned with reference to said receptacle discharge opening to receive the sand for its conveyance to a distant point of deposit, and water supply means for insuring a flow of sand through the hopper outlet comprising a main water supply conduit having a branch pipe projecting into said hopper at a point contiguous to said outlet, said last mentioned means being adapted to operate independently of the suction conduit and separating receptacle.
2. A sand barge having a sand containing hopper formed with a plurality of inter-valed discharge outlets, water supply means for insuring a flow of sand through the said outlets comprising a forcing device and a tubular connection extending therefrom to the outlets; a separating receptacle suitably supported in the barge above the plane of the outlets, a tubular connection between the outlets and the receptacle, and a suction device interposed in said last mentioned connection for producing a flow therein from the outlets to the receptacle, said forcing device being capable of operation independently of the suction device, substantially as and for the purpose set forth.
3. A sand barge having a sand containing hopper formed with a plurality of inter-valed discharge outlets in its base, a main water supply pipe located lengthwise of said base and provided with branch pipes extending through said hopper base adjacent the outlets to insure a flow of the sand therethrough, a localizing receptacle suitably supported in the barge above the hopper and said outlets and provided with an inlet opening and a discharge opening located below the inlet, a suction conduit connecting the hopper outlets and the inlet of the receptacle and operating independently of the main supply pipe, and transfer means operatively positioned with reference to the receptacle discharge opening to receive the sand therefrom and convey the same to a distant point of deposit.
4. A sand barge having a sand containing hopper formed with a discharge outlet, water supply means for insuring a flow of sand through said outlet comprising a forcing device and a tubular connection leading therefrom to the outlet, a separating receptacle or reservoir located independently of said means and formed with an upper intake opening and a lower sand discharge outlet, suction means for conducting the mixture from the hopper outlet to the intake opening for its separation in the receptacle, an over-flow pipe leading from the receptacle at a point adjacent the said intake opening, and a sand transfer device located in position with reference to the outlet of the said receptacle.

In testimony whereof I have hereunto signed my name in the presence of the two subscribed witnesses.
